UNITED STATES PATENT OFFICE.

STANISLAS ROUSSEAU, OF ALTON, ILLINOIS.

GAS-TURBINE.

1,300,026.

Specification of Letters Patent.

Patented Apr. 8, 1919.

Application filed December 31, 1917. Serial No 209,614.

To all whom it may concern:

Be it known that I, STANISLAS ROUSSEAU, a resident of the city of Alton, in the county of Madison and State of Illinois, have invented a new and useful Gas-Turbine Engine, of which the following is a specification.

My invention relates to turbine engines and has for its principal object to utilize the expansive force of exploding gases for driving the turbines. The invention consists principally in arranging a series of explosion chambers in communication with the jets of the turbine; and it further consists in the parts and combinations of parts hereinafter described and claimed.

In the accompanying drawing, which forms part of this specification and wherein like symbols refer to like parts wherever they occur,

Figure 1 is a vertical section of an engine embodying my invention, the section being taken on the line 1—1 of Fig. 4.

Fig. 2 is a horizontal view of said engine, the upper right-hand quarter of the figure being a plan view showing the upper portion of the cylinder head, the upper left-hand view being a plan view with the cylinder head removed, the lower left-hand view being a horizontal plan of the parts below the main body portion of the machine and the cam members and showing the gearing that transmits motion from the main shaft to the valve actuating cams; and the lower right-hand quarter of said Fig. 2 being a plan view illustrating the worm drive connection from the main shaft to the power transmission shaft. In this Fig. 2, the main shaft is shown in section in all but the first-mentioned quarter;

Fig. 3 is a vertical view partly in elevation and partly in section, illustrating mainly the piston actuating mechanism and the worm gear drive;

Fig. 4 is a horizontal sectional view following the irregular line 4—4 of Fig. 1;

Figs. 5, 6, 7 and 8 are detail views in vertical section illustrating the piston valve actuating mechanisms in various positions;

Fig. 9 is a detail sectional view illustrating the discharge passageway from the turbines on the line 9—9 in Fig. 2;

Fig. 10 is a detail sectional view on the line 10—10 in Fig. 11;

Fig. 11 is a detail side elevation of the

connection of the piston actuating rocker arm with its cam; and

Fig. 12 is the sliding block member of this connection.

The base 1 of my machine is provided with an anti-friction end thrust bearing 2 in which is stepped a vertical main shaft 3 that is provided with a worm 4. Meshing with this worm is a worm gear 5 mounted on a horizontal transmission shaft 6 which is itself mounted in journal bearings provided therefor in pedestals 7 in the base member 8 of the machine. This base member is made in the form of an oil-tight tank open at the top and provided with a filling opening in its side and a threaded plug 9 in said opening. By this arrangement, the tank may be partially filled with oil for the purpose of lubricating the worm gear.

Mounted upon the base member 8 is the body portion 10 of the framework. This body portion comprises an outer shell adapted for connection to the base portion and also adapted to receive the operating mechanism. This body portion has a horizontal partition or diaphragm 11 at the center of which is a bored hub 12 adapted to constitute a journal for the main shaft 3. Concentrically arranged with respect to this central hub is a series of vertically disposed cylinders 13 located close to the outer margin of the framework. Mounted on the main shaft 3 below said diaphragm so as to turn therewith is the cam mechanism hereinafter described; and above said diaphragm and also mounted on the shaft is a series of rotary turbines 14. Mounted on the body portion of the framework is the cylinder head 15, whose middle portion is formed into a journal bearing for the main shaft 3 and whose outer portions are provided with recesses 16 adapted to align with and constitute extensions of the respective cylinders 13. The cylinder head is provided with passageways 17 which extend from said recesses 16 (which are herein-after designated explosion chambers) and open into the turbine chambers so as to constitute passageways for the jets.

Each of the cylinders is equipped with valve mechanism and admission apparatus after the general manner of the ordinary internal combustion motor and also with suitable ignition apparatus; but the device is so arranged that the piston is not moved by

the force of the explosion, and the timing of the ignition is made with reference to this fact.

Each of the pistons is provided with a piston rod 18 which is connected by a heavy horizontal pin 19 to an oscillating link 20 which is pivotally mounted on a strong support 21 therefor mounted on the base portion of the machine so as to constitute a strong abutment. The framework of the machine is provided with a heavy rib 22 in position to constitute a limiting stop for the oscillating link when said link and the piston rod are in vertical position. Pivotally connected to the horizontal pin 19 is a short toggle link 23 which, in turn, is pivotally connected to a bell-crank lever 24 which is pivotally mounted on an angular support 25 that depends from and is fixed to the diaphragm 11 of the framework. The free arm of this bell-crank lever 24 has an elongated slot 26 therein in which fits slidably a flattened block 27. This flattened block 27 is pivotally mounted on a pin 28 which also has pivotally mounted thereon a similar block 29 that is slidably mounted in a vertically disposed frame 30 that depends from and is secured to the diaphragm of the framework. The inner end of said pin 28 projects beyond said slotted member 30 and is provided with a roller 31 or similar device which fits in a cam groove 32 provided therefor in the periphery of a cylindrical sleeve 33 that is mounted to rotate with the main shaft 3. Suitable spacing washers 34 are provided on the pin 28. This cam groove 32 is horizontal throughout the greater portion of its circumference, corresponding to the stage at which the piston rod 18 and link 20 are in vertical alignment and the piston is at the limit of its upward stroke. The cam groove 32 has one elevation designed to recharge the respective cylinders and compress the charges. In order to minimize shock, the support for the pivotal link 20 is bored out to receive a reciprocatable bumper member 35 and a helical spring 36 therefor, this bumper member 35 being so positioned that the pivotal link 20 will bear against it when said link approaches the limit of its stroke.

The mechanism for actuating the supply valves (of which there is one for each cylinder) is as follows: The supply passage 37 has an inlet port leading upwardly into the explosion chamber 16 and provided with a valve seat for a reciprocating valve 38. The stem 39 of this valve extends vertically downward and is provided with a helical spring 40 surrounding the same and adapted to bear upwardly against a stationary part and downwardly against a pin on the valve stem so as to keep the valve normally seated. The lower end of the valve stem 39 is provided with an adjustable end

member 41 which bears against the upper edge of a rocker arm 42 pivotally mounted on the framework and provided with a roller 43 at its free end. This roller 43 is positioned to bear on the upper edge of a cam ring 44 that is fixed to a spider 45 or other support that is operatively secured to the main shaft to rotate therewith. This upper edge of the ring 44 is horizontal throughout the greater portion of its length 75 corresponding to the closed position of the supply valve 38 but is provided with a rise or cam surface 46 adapted to lift the valve once in each revolution of the main shaft 3. As the purpose of this lifting of the supply 80 valve is to charge the cylinder, the rise or cam portion of the ring is so positioned that the lifting action of the supply valve will be timed to coincide with the downward stroke of the piston, the discharge 85 valve meanwhile being closed.

In the construction illustrated in the drawings, the support for the cam ring 44 is mounted on a hub 47 that is journaled concentric with the main shaft 3 and rests 90 on an anti-friction bearing 48 provided therefor on the base of the machine. On the lower surface of this spider or hub is mounted an internally threaded gear ring 49, which meshes with the spur gear 50 on a 95 shaft which carries a second spur gear 51, which in turn meshes with the spur pinion 52 mounted on the main shaft.

The mechanism for operating the discharge valves (of which there is one for 100 each cylinder) is as follows: The discharge valve 53 is a cylindrical plug with a wide segment cut out of one of its sides. This valve is mounted on a vertical axis in the discharge passageway 17, which is normally 105 open but which is adapted to be closed by said valve when turned into the proper position for the purpose. The stem 54 of this discharge valve extends downwardly and on its free end is a lever 55 which is pivotally 110 connected to a pair of links 57 which in turn are connected to a slide 58 radially disposed in a slideway 59 provided therefor on the diaphragm 11 of the framework. The inner end of this slide is provided with 115 a roller 60 or bearing member that fits in a groove 61 in the upper surface of a ring 62 that is operatively connected to the main shaft 3 to be driven thereby. This groove 61 is circular throughout a considerable 120 portion (say, one-half) of its circumference and has a single rise 63 or eccentricity whereby the valve stem is adapted to be oscillated once in each revolution of the main shaft. The angular position of the 125 eccentricity of this discharge valve cam relative the operative portions of the other cams is such that the discharge valve will be closed while the supply valve is open.

The operation of the machine is as fol- 130

lows: Assuming that the piston is in its lowermost position, the inlet valve 38 is open and the discharge valve is closed, and accordingly the cylinder receives its 5 charge. As the piston begins to move upwardly, the supply valve is closed, but the discharge valve also remains closed until the charge has been fully compressed. In 10 this position, the piston rod 18 and the link 20 are in alinement and the toggle link 23 is prevented from moving by reason of its cam connections. In this position, the charge is ignited simultaneously with the opening of the discharge valve 53, whereupon 15 the products of combustion are discharged through the jet opening 17 against the vanes of the turbine wheels after the manner of the ordinary turbine engine. The main shaft is thus rotated, carrying with it 20 the valve actuating cams and also the worm 4 which transmits power through the worm gear to the transmission shaft 6. When the main shaft has rotated to the predetermined angle, the piston actuating cam causes the 25 piston to be moved downwardly and the discharge valve 53 to be closed and the supply valve 38 to be opened simultaneously. By this arrangement, the cylinder is recharged whereupon the supply valve is closed, the 30 discharge valve meanwhile remaining closed, and the piston moves upwardly to its initial position, compressing the charge and thus completing its cycle of operation. This same cycle occurs with each of the several 35 cylinders.

Obviously, the construction hereinbefore described admits of variation without departing from my invention.

What I claim is:

40 1. A gas turbine engine comprising a main shaft, turbine mechanism therefor, a plurality of explosion chambers whose discharge passageways are arranged to constitute jet openings for said turbine mechanism, and means for charging and discharging said explosion chambers respectively, each of said means comprising a cylinder communicating with its explosion chamber, a piston in said cylinder, a toggle for positioning the piston and means for controlling 45 the toggle.

50 2. A gas turbine engine comprising a main shaft, turbine mechanism therefor, a plurality of explosion chambers whose discharge passageways are arranged to constitute jet openings for said turbine mechanism and means for charging and discharging said explosion chambers respectively, each of said means comprising a cylinder 55 communicating with its explosion chamber, a piston in said cylinder, a toggle for positioning the piston and means for keeping the spreading members of the toggle in alinement with the piston during ignition 60 and discharge.

3. A gas turbine engine comprising a main shaft, turbine mechanism therefor, a plurality of explosion chambers whose discharge passageways are arranged to constitute jet openings for said turbine mechanism, and means for charging and discharging said explosion chambers respectively, each of said means comprising a cylinder communicating with its explosion chamber, a piston in said cylinder, a toggle for positioning the piston, 70 inlet and discharge valves for said explosion chamber, and means for actuating said valves and toggle, said means being adapted to hold said piston in its advanced position during ignition and discharge. 80

4. In a gas turbine engine wherein a plurality of explosion chambers have their discharge passageways adapted to constitute jet openings for the turbine elements, cylinders in operative relation to said explosion chambers, pistons in said cylinders, piston rods, links pivotally mounted on fixed abutments in axial alinement with said cylinders and pivotally connected to said piston rods, and means for keeping said links and rods in 85 alinement during ignition and discharge. 90

5. A turbine engine in combination with internal combustion engines disposed parallel with the main turbine shaft and adapted to discharge through the jet openings of the turbine and controlling mechanism operatively connected to said main shaft and to the supply and discharge valves of the internal combustion engines and to the pistons thereof, each of said supply valves being a reciprocatable spring pressed valve disposed parallel with said shaft and having an adjustable end member, levers disposed transversely of said shaft in operative relation 95 to the respective end members, and a cam mounted on the main shaft and operatively engaging said levers to operate the same and thereby actuate the respective supply valves. 100

6. A gas turbine engine comprising a main shaft, turbine mechanism therefor, a plurality of explosion chambers whose discharge passageways are arranged to constitute jet openings for said turbine mechanism, and means for charging and discharging said explosion chambers respectively, each of said means comprising a cylinder communicating with its explosion chamber, a piston in said cylinder, a toggle for positioning the piston and means for controlling 105 the toggle, a rotary member having a cam groove therein, a stationary member having a slot therein extending parallel with the main shaft, a rocker arm having one arm pivotally connected to said toggle link and having a longitudinal slot in its other arm, and a pin extending through said slots and into said cam groove. 115

7. A gas turbine engine comprising a main shaft, turbine mechanism therefor, a plu- 120

- 4
8. A gas turbine engine comprising a main shaft, turbine mechanism therefor, a plurality of explosion chambers whose discharge passageways are arranged to constitute jet openings for said turbine mechanism, and means for charging and discharging said explosion chambers respectively, each of said means comprising a cylinder communicating with its explosion chamber, a piston in said cylinder, a toggle for positioning the piston and means for controlling the toggle, a rotary member having a cam groove therein, a stationary member having a slot therein extending parallel with the main shaft, a rocker arm having one arm pivotally connected to said toggle link and having a longitudinal slot in its other arm, a pin extending through said slots and into said cam groove, and a yielding bumper for said toggle.
9. A gas turbine engine comprising a main shaft, turbine mechanism therefor, a plurality of explosion chambers whose discharge passageways are arranged to constitute jet openings for said turbine mechanism, and means for charging and discharging said explosion chambers respectively, each of said means comprising a cylinder communicating with its explosion chamber, a piston in said cylinder, a toggle for positioning the piston and means for controlling the toggle, a rotary member having a cam groove therein, a stationary member having a slot therein extending parallel with the main shaft, a rocker arm having one arm pivotally connected to said toggle link and having a longitudinal slot in its other arm, a pin extending through said slots and into said cam groove, and a back-stop for said toggle.
8. A gas turbine engine comprising a main shaft, turbine mechanism therefor, a plurality of explosion chambers whose discharge passageways are arranged to constitute jet openings for said turbine mechanism, and means for charging and discharging said explosion chambers respectively, each of said means comprising a cylinder communicating with its explosion chamber, a piston in said cylinder, a toggle for positioning the piston and means for controlling the toggle, a rotary member having a cam groove therein, a stationary member having a slot therein extending parallel with the main shaft, a rocker arm having one arm pivotally connected to said toggle link and having a longitudinal slot in its other arm, a pin extending through said slots and into said cam groove, and a back-stop for said toggle.
9. A gas turbine engine comprising a main shaft, turbine mechanism therefor, a plurality of explosion chambers whose discharge passageways are arranged to constitute jet openings for said turbine mechanism, and means for charging and discharging said explosion chambers respectively, each of said means comprising a cylinder communicating with its explosion chamber, a piston in said cylinder, a toggle for positioning the piston and means for controlling the toggle, a rotary member having a cam groove therein, a stationary member having a slot therein extending parallel with the main shaft, a rocker arm having one arm pivotally connected to said toggle link and having a longitudinal slot in its other arm, a pin extending through said slots and into said cam groove, and a yielding bumper for said toggle.
- Signed at Alton, Ill., this 21 day of December, 1917.
- STANISLAS ROUSSEAU.
